C. E. PARKHURST

DENTIST'S WATER HEATER

Filed May 20, 1922

Fig. 4.

Inventor:
Charles E. Parkhurst,
by Roberts, Roberts & Cushman
attys.

UNITED STATES PATENT OFFICE.

CHARLES E. PARKHURST, OF SOMERVILLE, MASSACHUSETTS.

DENTIST'S WATER HEATER.

Application filed May 20, 1922. Serial No. 562,491.

To all whom it may concern:

Be it known that I, CHARLES E. PARKHURST, a citizen of the United States of America, and resident of Somerville, in the county of Middlesex and State of Massachusetts, have invented new and useful Improvements in Dentists' Water Heaters, of which the following is a specification.

This invention relates to water heaters and consists of a water heater especially adapted to be employed for supplying water for oral use by dental patients.

It is found in practice that water heaters using gaseous or liquid fuel give off when in operation a disagreeable odor regardless of whether the water is being raised to a high or low temperature. By reason of the fact that water for oral use in dental surgery is to be raised only to a moderate temperature it is desirable that the heater be conveniently located so that the dentist himself can control its operation. The odor, however, produced by such devices becomes so unpleasant and offensive in the small rooms ordinarily used by dentists as to practically preclude their use.

Objects of the invention are to heat water to a moderate temperature rather than to a high temperature as in usual type of water heaters, to obviate the disagreeable odor produced by such devices, to provide means for accurately controlling the temperature of the heated water, and in general to improve devices of this kind and render them satisfactory and efficient in service.

The invention comprises a water heater having a casing, a water coil and a fuel burner in the casing, and means producing complete combustion of the fuel without direct contact of the flame with the heating coil. While the means may comprise apparatus for directing the flame downwardly, or a gap or space in the water coil, or an enlargement of the casing, it preferably comprises a combination of all three. The invention further comprises means for preventing water of condensation from interfering with the operation of the burner and producing incomplete combustion of the fuel.

For the purpose of illustrating the invention one concrete embodiment thereof is shown in the accompanying drawings, in which;

Fig. 1 is a front elevational view;

Fig. 2 is a vertical section through the heater;

Fig. 3 is a plan view with the top of the casing removed;

Fig. 4 is an elevational view of the burner;

Fig. 5 is a section on the line 5—5 of Fig. 4.

The embodiment of the invention shown for the purpose of illustration comprises a dentist's water heater adapted to be attached to the standard upon which the dentist's cuspidor is mounted and to be supplied with water from the supply pipe to the latter. The preferred form of heater is shown in the accompanying drawings in which A indicates the casing, B the water supply pipe and C the fluid fuel pipe. The supply of water is controlled by a valve 4, the supply of fuel, preferably gas, by a valve 5 and both valves are preferably simultaneously operated by a valve spindle 6 actuated by handle 7. Within casing A is a burner 8 connected to the fluid supply valve 5 by a transverse pipe 9 in the base of the casing having an opening 10 through which the gas enters the burner, pipe 9 being in turn connected to a pipe 11 which leads directly to valve 5. A pilot burner 12 is likewise supplied from a smaller pipe 13 which connects directly with the fuel supply pipe 6.

The water supply pipe 14 leading from valve 4 enters the base of the casing through an opening 15 and is attached to a water tube of suitable material, such as copper, which forms the water coil within the casing. The lower portion of the coil is arranged in circular convolutions 16 about the base of burner 8 and adjacent the casing A and thence leads upwardly by a substantially vertical section 17 to a point adjacent the top of burner 8 and is there formed in a coil 18 arranged to substantially fill the upper portion of the casing as clearly indicated in Fig. 3 which shows the upper portion of the casing in plan.

As shown the tubing is arranged in convolutions, each convolution having a number of loops 19, these loops being staggered in adjacent convolutions so that in plan view the upper water coil provides a central or axial opening 20 directly above the burner 8 and a plurality of openings 21, in the form shown seven in number, parallel to the central opening 20 through which the heated

gases from the fuel burner may pass. The upper and lower portions of the water coil may be separated or held in spaced relation from the sides of the casing by spacers 22 which may take the form of corrugated cylindrical plates of sheet material. The upper coil 18 connects at 23 to a faucet 24 having two openings 25 and 26 controlled by a single valve 27. Opening 25 is arranged to 5 extend over the cuspidor and is used to fill the glass ordinarily supported on a bracket. The opening 26 is arranged to have a syringe tube attached thereto for oral work by the dentist. A thermometer 28 may be mounted 10 in the connection to the syringe opening 26 to guide the dentist in making the proper adjustment of handle 7 to maintain the water issuing through the syringe opening at the proper or desired temperature. The 15 base 29 and the top 30 of the casing are supplied with air openings 31 and are preferably detachable from the casing A, being held thereon by clamping screws 32.

As indicated in Fig. 2 the burner openings 33 are downwardly inclined whereby the flame is caused to be directed downwardly and outwardly fanwise into the space or gap provided between the lower and upper coils 16 and 18 of the water tubing. At this 20 point the casing A preferably has an enlargement or bulge 34 providing an enlarged space in the region of the flame and substantially coincident with the gap between the coils.

35 In order that water of condensation may not gather upon the top of the burner and then run down clogging openings 33 and causing imperfect combustion of the fuel, inefficient operation and possible odor, a 40 hood or cap 35 is provided upon the top of the burner, integral therewith or fast thereon as by a threaded shank 36 fitting in a threaded axial opening in the top of burner 8. Cap 35 may be of any suitable shape but 45 in the form shown is conical with its base spaced from the top of the burner and overhanging the sides of the latter sufficiently so that water dripping from the peripheral edge thereof will not reach the burner. The base of the cap between shank 36 and edge 37 is preferably recessed as indicated at 38 so that the water gathering on the edge will not find its way to the shank and thence to the burner. To prevent water 50 of condensation from dripping from the coils and from cap 35 to the floor a drip pan 39 is provided directly beneath the casing from which the drain pipe 40 leads to the dentist's cuspidor.

60 From the above it will be evident that the flame issuing from the burner does not come directly in contact with the water coils and that the provision of the enlarged chamber and the downward diverting of the flame 65 thereinto tends to cause the fuel to be en-

tirely consumed therein so that only the heated gases pass upwardly through openings 20 and 21 in the upper coil 18.

The particular form and arrangement of the burner, the coils and heater casing were 70 developed only after extensive experimentation for the purpose of overcoming the objectionable odor heretofore always present in fluid operated water heaters. The downward diverting and spreading of the flame 75 tends to confine it to the immediate region of the burner. The gap or space between the upper and lower portions of the water coil prevents the flame from coming in direct contact with the coil. The enlargement 80 of the casing provides sufficient air and space for the complete combustion of the fuel. While it is not clear whether the particular form of burner, the particular form of coils, the particular form of casing or the 85 cap for the burner contributes most to the successful operation of the heater, the tests conducted with various forms of these essential parts seem to indicate that the odor is obviated only by the combination of all 90 of these features. The dimensions of the water coils, the burner and the control valves 4 and 5 are such that water at any desired temperature may be drawn from faucet 24 within the range of the device 95 which varies from a temperature only slightly above that of the water in supply pipe C to a maximum of about 140° F.

From the above it will be evident that a 100 convenient odorless heater of suitable size for use by dentists has been developed for raising water to the moderate temperature required in dental surgery and that the provision of the simultaneous control of the feed valves, water and fuel, permits 105 convenient control of the apparatus, which control may be very accurate as to the temperature of water supplied when the syringe connection is used due to the provision of the thermometer 28. 110

I claim:

1. A water-heater comprising a casing having air openings at its upper and lower ends and a central enlargement, a water tube coiled in the upper and lower portions of said casing, a burner axially disposed in said casing terminating adjacent said enlargement and arranged to direct the flame downwardly and outwardly in the region of said enlargement in a direction away from the 120 proximate coils.

2. A water-heater comprising a casing having air openings at its upper and lower ends and a central enlargement, a water coil disposed in said casing below said enlargement, a second water coil substantially filling the space above said enlargement but providing longitudinal openings there-through, means for catching and carrying away the water of condensation which drips 125 130

from said coils, and a burner arranged in said casing to direct the flame downwardly into the space provided by said enlargement between the coils and not into direct initial contact therewith.

3. A dentist's water-heater comprising a casing having air openings at its upper and lower ends and a central enlargement, a water coil in said casing spirally disposed below said enlargement, a second water coil substantially filling the space above said enlargement but having longitudinal openings therethrough, means spacing said coils from said casing to provide air passages therebetween, a burner axially disposed in said casing and arranged to direct a single circle of flame downwardly and fanwise into the space provided by said enlargement, said burner cooperating with the enlargement and the disposition of the coils to prevent the flame from initially reaching the coils thereby to prevent disagreeable odors.
4. A water-heater comprising a casing having air openings at its upper and lower ends and a central enlargement, a water coil disposed in said casing below said enlargement, a second water coil substantially fill-

ing the space above said enlargement but providing longitudinal openings therethrough, a burner arranged in said casing intermediate the coils to direct the flame downwardly into the space provided by said enlargement between the coils and not into direct contact therewith, and a cap upon the top of said burner overhanging the sides thereof to prevent water of condensation from the overlying coil from reaching the burner openings and interfering with the combustion of the fuel.

5. A water-heater comprising a casing having air openings at its upper and lower ends and a central enlargement, a water tube coiled in the upper and lower portions of said casing, a burner axially disposed in said casing terminating adjacent said enlargement and arranged to direct the flame downwardly and outwardly in the region of said enlargement, and a member extending over and beyond the sides of the burner to prevent water of condensation on the upper coil from dripping thereon.

Signed by me at Boston, Mass., this 16th day of May, 1922.

CHARLES E. PARKHURST
